C. P. RANDOLPH

ELECTRIC HEATER

Filed May 25, 1925

Fig. 2.

Inventor
Charles P. Randolph
by *Alfreda S. Lint*
His Attorney

UNITED STATES PATENT OFFICE.

CHARLES P. RANDOLPH, OF OAK PARK, ILLINOIS, ASSIGNOR TO EDISON ELECTRIC APPLIANCE COMPANY, INCORPORATED, OF CHICAGO, ILLINOIS, A CORPORATION OF NEW YORK.

ELECTRIC HEATER.

Application filed May 25, 1925. Serial No. 32,529.

To all whom it may concern:

Be it known that I, CHARLES P. RANDOLPH, a citizen of the United States, residing at Oak Park, in the county of Cook, 5 State of Illinois, have invented certain new and useful Improvements in Electric Heaters, of which the following is a specification.

My invention relates to electric heaters, more particularly to electric flatirons, and 10 has for its object the provision of a simple and reliable device of this character which may be manufactured at low cost.

In carrying out my invention I secure an insulating heating resistance conductor in 15 a groove in the top of the body to be heated.

For a more complete understanding of my invention reference should be had to the accompanying drawing in which Fig. 1 is a sectional view of an electric flatiron embodying my invention while Fig. 2 is a plan view with the cover and various other parts removed showing the arrangement of the heating unit.

Referring to the drawing, in the form of 25 my invention disclosed I have shown a mass of heat conducting material 10, such as cast iron, forming a flatiron body of conventional outline and being provided on its lower side with an ironing face 11. The flatiron 30 body 10 is provided at the top with a central upwardly projecting portion 12 having substantially the same outline as the lower portion whereby a ledge 13 is formed around the flatiron body on which rests a suitable 35 cover 14. The cover is secured to the flatiron body by means of screws 15 and 16. These screws also pass through and secure a suitable handle 17. The cover 14 is centrally located on the flatiron body by means 40 of stops or projections 18 to 22 inclusive spaced along the sides of the raised portion 12.

In the upper surface of the raised portion 45 12 a groove 23 is provided, having substantially the same outline as the flatiron body. As shown, the groove is substantially horse-shoe shaped, its two ends being at the heel of the flatiron body and terminating with the heel of the raised portion 12. The 50 groove is provided with a substantially flat bottom and with substantially vertical side walls, and is substantially square, i. e. its width is equal to its depth.

Mounted in the groove 23 is a resistance 55 heating unit 24. This heating unit 24 is

constructed substantially in accordance with the invention described and claimed in Patent No. 1,367,841 to Abbott dated February 1, 1921, it being provided with a continuous, unbroken outer metallic sheath 60 25 in which is a helical resistance conductor 26 embedded in powdered electrically insulating material 27. The sheath 25 is preferably formed of seamless tubing. The powdered insulating material is compacted 65 to a hard dense mass by reducing the diameter of the sheath, for example, by rolling or swaging, and forms an excellent insulator and also an efficient conductor of heat from the resistance conductor to the 70 sheath. In the arrangement shown the sheath is shaped with a substantially square cross section and is of such size as to fit quite closely in the groove 23.

A clamping plate is provided having its 75 edge bent downward so as to form a ridge 29, which rests on the heating unit 24. This clamping plate is secured to the body 10 by means of screws 30, and the heating unit is thereby clamped firmly in the groove. 80 It will be observed that the lower flat side of the heating unit is pressed firmly against the flat bottom of the groove and is thus maintained in good thermal relation therewith. The sides of the groove are in close 85 proximity to the heating unit and receive a certain amount of heat by radiation and conduction. The flatiron body 10 is preferably cast, the groove 23 being formed in it upon casting. The only machine work 90 necessary, therefore, is that required to finish the ironing face 11.

The resistance conductor 26 has its ends connected to terminal members 31 and 32 which in turn are connected to contact pins 95 33 carried by the cover 14. A suitable guard 34 surrounds the contact pins. An electrical connection is established between a suitable supply circuit and the contact pins by means of an attachment plug of 100 any well known form.

It will be observed that my invention lends itself to a simple and rugged low cost construction throughout the device. The heating unit, which is the most prolific 105 source of trouble in electric appliances, is of particularly rugged construction. The arrangement of the heating unit with respect to the heated body permits the efficient conduction of heat from the resistance con- 110

ductor to the heated body, facilitates the production of the heated body at low cost, and promotes ease and quickness of assembly. Furthermore, the heating unit can 5 be removed very easily at any time for repairs or renewal.

While I have described my invention as embodied in concrete form and as operating in a specific manner in accordance with the 10 provisions of the patent statutes, it should be understood that I do not limit my invention thereto, since various modifications thereof will suggest themselves to those skilled in the art without departing from 15 the spirit of my invention, the scope of which is set forth in the annexed claims.

What I claim as new and desire to secure by Letters Patent of the United States, is:—

1. The combination with a mass of heat 20 conducting material provided with a substantially flat-bottom groove, of a heating unit encased in a continuous unbroken metallic sheath clamped in said groove, said sheath being formed with a substantially 25 flat surface held in engagement with the bottom of said groove in good thermal relation therewith.

2. The combination with a mass of heat 25 conducting material provided with a flat-

bottom groove having a depth substantially 30 equal to its width, a resistance conductor encased in a continuous unbroken metallic sheath shaped to have a substantially square cross section fitting closely in said groove, and means for clamping said sheath in said 35 groove so that one side thereof is held in intimate thermal relation with the bottom of said groove.

3. The combination with a mass of heat 40 conducting material provided with a flat-bottom groove having a depth substantially equal to its width, a helical resistance conductor, a sheath of seamless metal tubing surrounding said resistance conductor, powdered heat refractory insulating material in 45 said sheath compacted to a hard dense mass around said resistance conductor by reducing the diameter of said sheath, said sheath being shaped during the reducing operation to have a substantially square cross section 50 fitting closely in said groove, and means for clamping said sheath in said groove so that one side thereof is held in intimate thermal relation with the bottom of said groove.

In witness whereof, I have hereunto set 55 my hand this 21st day of May, 1925.

CHARLES P. RANDOLPH.
